corporation of California

Filed Mar. 13, 1961, Ser. No. 64,238

Term of patent 14 years

(Cl. D30—1)

FIG. 1.

FIG. 2.

FIG. 3.

FIG. 4.

FIG. 1 is a top plan view of a recoil pad for firearms, showing my new design;

FIG. 2 is a side view of FIG. 1, the opposite side being the same;

FIG. 3 is a left end elevation of FIG. 2; and

FIG. 4 is a right end elevation of FIG. 2.

The essential features of the design reside in the face portion of the pad shown in solid lines.

I claim:

The ornamental design for a recoil pad for firearms, substantially as shown and described.
